ALBERT C. PAULSMEIER, OF ALAMEDA, CALIFORNIA, ASSIGNOR TO BYRON JACKSON
IRON WORKS, OF WEST BERKELEY, CALIFORNIA, A CORPORATION OF CALIFORNIA.

DEEP-WELL-PUMP COLUMN.

1,301,597.

Specification of Letters Patent. Patented Apr. 22, 1919.

Application filed November 24, 1914. Serial No. 873,770.

To all whom it may concern:

Be it known that I, ALBERT C. PAULSMEIER, a citizen of the United States, residing at Alameda, in the county of Alameda 5 and State of California, have invented new and useful Improvements in Deep-Well-Pump Columns, of which the following is a specification.

This invention relates to pumps, and particularly to means for conveying the liquid from the pump to the point of discharge and for suspending the pump column in the well.

In deep well pumps of the so-called incased line shaft type, such as shown in Patent #986,827, dated March 14, 1911, issued to Frank H. Jackson, it has been common to use a separate discharge pipe for the water lifted upward by the impeller; that is, the pump equipment has included the shaft, a tube to surround and protect the shaft, and then a second tube concentric with or eccentric to the shaft-protecting tube and constituting a discharge for the water from the pump case to point of delivery. I propose doing entirely away with the discharge tube or pipe and utilizing the well casing itself for the purpose. Another and the main object of the invention is to provide a flexible, self-adjusting, self-centering packing or diaphragm, between the pump and well casing, to support the pump at any desired point in the well. A further object is to improve the column construction itself. Further objects will hereinafter appear.

The invention consists of the parts and the construction and combination of parts as hereinafter more fully described and claimed, having reference to the accompanying drawings, in which—

Figure 1 is a partial central section through the pump and well, showing the application of the invention.

Fig. 2 is an enlarged section of the pump, showing the position of the cup leather.

Fig. 3 is a slight modification, showing the application of the cup leather where the pump is of smaller diameter than the well casing.

1 indicates a pump of the centrifugal type (including case and impeller); 2 the well casing; 3 the pump shaft revolved by any suitable means (not here shown); and 4 a sectional shaft tube in which the tube couplings 5 and bearings 6 are mounted, the tube 4 and shaft constituting the pump col-

umn being suspended from the pump head 7. Tube 4 is open at the top. It is made in sections of appropriate length with a bearing coupling 5 connecting them. Each coupling, it is observed, forms a bearing, doing away with all spiders, flanges, etc. The result is that the shaft and tube are under heavy tension, due to their own weight and the weight of the water, thereby insuring proper alinement and operation without warping or whipping of the shaft. The top of the well casing is surmounted by the discharge 8.

Formed on the upper end of the case of pump A is a flange 10 on which is secured, by means of a ported follower ring 11, a large cup leather or flexible diaphragm 12, of sufficient size and so constructed and arranged that when exposed on the top side to water pressure it will expand tightly against the walls of the well casing 2, adjusting itself to any slight inaccuracy even though there may be rivet heads or joints in the pipe. There may be cases when a slight leakage takes place, but that is easily counteracted by reason of the fact that the friction in the casing will be a good deal less than it is when a common discharge pipe is used; the area of the well casing being much larger than where a separate discharge pipe is used.

The follower ring 11, by which the cup leather is secured, is angular in cross section with the vertical flange provided with a plurality of large slots 13 which prevent sand from collecting between the follower ring and the diaphragm 12; the water discharging through same preventing the sand from collecting and forcing it out with the water. The water from the pump impeller passes upward through passages 14 and through the central opening in the follower ring 11 to the discharge.

If the well should be much larger than the diameter of the pump, a separate plate 14' (Fig. 3) is first secured upon the pump flange 10, the diameter of said plate being sufficiently large to suit the particular well. The flexible diaphragm 12 is of larger diameter than plate 14' and is secured by a follower ring 11 similar to that indicated in Fig. 2. The pump itself may, in this instance, remain of standard size.

In lowering the pump into the casing, it is most desirable to place it in a position

where, when operating and giving the quantity called for, it will be submerged about up to the point of the diaphragm cup leather 12, *i. e.* just submerged, as thereby there will never be any trouble during the time of operation. The pump when not in operation will be submerged, as the water accumulating will pass through and over same. There will in that instance be no pressure against the inner side of the diaphragm 12 because everything will be neutralized; but the moment the pump starts, the column of water above the diaphragm will immediately rise, while the water below will have a tendency to drop, thus creating sufficient pressure on the inner upper side of the diaphragm to force this against the well casing and form a joint sufficiently tight to support the discharging water column.

Thus it can be seen that the flexible diaphragm 12, conveniently illustrated as a cup leather construction because of its simplicity and practicability, constitutes an automatically expandible partition carried by the pump, coöoperating with the well casing to divide the well into upper and lower compartments, the upper of which constitutes the discharge column of the pump, thereby eliminating the use of a separate pipe for the discharging water and consequently reducing the cost of manufacture and installation.

This construction furthermore produces an installation of considerable flexibility; that is, one that may be inserted into crooked casings and adjusted to varying water levels. In other words, it is immaterial whether the pump shaft and pipe are exactly in the center of the well or not, as long as it is in the center at the point where the diaphragm is attached to the pump, since the diaphragm will form a flexible, self-adjusting, self-centering support for the pump and a packing and partition for the water column above against return below the pump.

The protective tubing 4 is not designed or intended to exclude the water from around the shaft, but merely to protect the latter from interference by foreign matter in the well and provide an easy method of suspension and lubrication. Accordingly the tubing, in addition to being open at the top, is open to the water in the well at the bottom through ports 16 and 17 in the pump case; the strainer 18 serving to prevent the entry of grit and other foreign matter into the tubing 4 and shaft bearings. Consequently the water in the tube is maintained at all times at the same level as the water in the well when the water is above the diaphragm 12.

20 is a port extending radially through the pump case as seen in Fig. 2, connecting the chamber 21 between the gland 22 and

shaft bearing 23 with the water space in the well. The purpose of this port 20 is to vent any water that would otherwise be forced by the action of the impeller up past the gland and bearing into the tubing 4, with the result under some conditions, of displacing all the oil in the inner tube and also cutting the bearing 23. It is to be understood that in the operation of these pumps the impeller exerts a considerable upward pressure dependent upon the head pumped against tending to force water along the pump shaft 3 and up through the tube 4 and bearings 6 in which the shaft turns. This pressure unless controlled, or taken care of, is sometimes sufficient to fill the inner tube 4, particularly if this tube is closed off at the bottom from communication with the well, and cause an overflow at the top of the column 4, washing out the lubricant. The bleed port 20 takes care of this relief.

It also prevents sand and grit from getting into the bearing 23 and cutting it out. This is quite an important feature.

The spring 24 in chamber 21 is designed automatically to take up any wear of the packing 22.

Having thus described my invention, what I claim and desire to secure by Letters Patent is—

1. In a deep well pump, the combination of an outer casing, a line shaft, a tube surrounding and spaced from the shaft, an impeller secured to the shaft, a casing inclosing the impeller and supported by the tube, said shaft and tube, together with the impeller and its casing being suspended from above entirely independent of the outer casing, whereby the tube and shaft are placed in tension and independent of the casing, and a diaphragm member connected with the pump and coacting with the casing to center the pump within the casing.

2. In a deep well pump, the combination of an outer casing, a line shaft, a tube surrounding and spaced from the shaft, an impeller secured to the shaft, a casing inclosing the impeller and supported by the tube, said shaft and tube, together with the impeller and its casing being suspended from above entirely independent of the outer casing, whereby the tube and shaft are placed in tension and independent of the casing, and a diaphragm member connected with the pump and coacting with the casing to form with the casing a water discharge for the pump.

3. In a deep well pump, the combination of an outer casing, a line shaft, a tube surrounding and spaced from the shaft, an impeller secured to the shaft, a casing inclosing the impeller and supported by the tube, said shaft and tube, together with the impeller and its casing being suspended from above entirely independent of the outer casing,

whereby the tube and shaft are placed in tension independently of the outer casing and a diaphragm member connected with the pump casing and coacting with the outer casing to center the pump within said outer casing.

4. In a deep well pump, the combination of an outer casing, a line shaft, a tube surrounding and spaced from the shaft, an impeller secured to the shaft, a casing inclosing the impeller and supported by the tube, said shaft and tube, together with the impeller and its casing being suspended from above entirely independent of the outer casing

whereby the tube and shaft are placed in tension independently of the outer casing, and a diaphragm member connected with the pump casing and coacting with the outer casing to form with said outer casing a water discharge for the pump.

In testimony whereof I have hereunto set my hand in the presence of two subscribing witnesses.

ALBERT C. PAULSMEIER.
